The ornamental design for a bottle, as shown and described.

DESCRIPTION

FIG. 1 is a top, front perspective view of a bottle showing our design;

FIG. 2 is a front view thereof;

FIG. 3 is a right side view thereof, the bottle having been rotated 45-degrees in a clockwise direction about its central axis;

FIG. 4 is a left side view thereof, the bottle having been rotated 45-degrees in a counter-clockwise direction about its central axis;

FIG. 5 is a top plan view thereof; and,

FIG. 6 is a bottom plan view thereof.

In the FIG. 2, the broken lines showing a nipple and a nipple seating ring illustrate environmental elements of the bottle which form no part of the claimed design.
